LOCK FOR AUTOMOBILE DOORS

Ferruccio Accardi, Turin, Italy, assignor to Fiat
Società Anonima, Turin, ItalyApplication July 26, 1935, Serial No. 33,401
In Italy October 10, 1934

2 Claims. (Cl. 292—34)

This invention relates to a lock for automobile doors.

The handles of these locks generally rotate about a pivot extending perpendicularly to the door surface and project considerably from the plane of said surface, limiting the lateral clearance of the body, catching some part of the users' clothes and spoiling the line of the car.

According to this invention the handle rotates about a pivot parallel to the plane of the door and the lock opens by the simple outward swinging of the handle. The handle and its pivot can be lodged in a recess in the door surface and provision is made for permitting the handle end 5 to be caught by one finger and pulled outward for opening the door by enlarging the recess on one side or causing the handle end to project slightly to the outside.

The drawing shows diagrammatically by way of example a lock embodying two vertically sliding rods.

Figure 1 is an elevation.

Figure 2 is a vertical longitudinal section.

Figure 3 is a horizontal cross section on line A—O—P—B of Figure 2.

Figure 4 is a sectional view showing details of the latch operating mechanism.

Figure 5 is a sectional view taken at right angles to Figure 4.

The door is opened and closed by the longitudinal displacement of the rods 3a. This longitudinal displacement is effected by the rotation of the disc 4 lodged in the case 2 and connected to the sliding rods 3a by the links 3. The disc 4, which is connected to the handle 5 for opening the door from the inside of the car, is provided with two diametrically opposite slots 20, in which fit pins 21 arranged on the links 3. A spring 22 acting on a roller 23 rotatably mounted on a pin 24 fixed to the disc 4 tends to carry the latches into the closing position shown in Fig. 1. On the face opposite to that carrying the spring, the disc carries a pin 6 cooperating with the concealable handle 7. The disc 4 is rotated from the inside of the car by turning the handle 5 which is of the usual type, and from the outside of the car by swinging the handle 7 outward. The eccentric pin 6, carried by disc 4 is acted upon by a finger 9 on the handle 7.

50 The handle 7 is parallel to the pivot of rotation 8 of the handle and to the door surface. By the action of a spring 10 the finger 9 is held against the pivot 6 of the disc 4 so that the oscillation of the handle to the position 7' brings about a rotation 45 of the disc 4 to open the lock. The handle 7 is sunk into recess 11 in the door. The handle end 1a is slightly bent outward and to move the

handle this end 1a is caught from behind by the tip of the first finger. To permit this manipulation without bending the handle end 1a excessively, the recess 11 is enlarged at its end 12. The pivot 8 is carried invisibly by a light ferrule 13, secured to the door and a stop 14 is provided for the handle 7. The rubber pad 15 for the door and the window panel 16 are also visible on Figure 3.

What I claim is:

1. In an automobile door, safety latching means comprising a pair of locking bolts, a disc pivotally mounted in said door and adapted to be rotated by a knob on the inner side of said door, pin and slot connections between said bolts and said disc whereby rotation of said disc is effective to operate said bolts, means acting on said disc to hold said bolts in their locking positions, an eccentric pin on the outer side of said disc, said door having a recess in the outer surface thereof, a handle mounted in said recess substantially flush with the outer surface of the door when said handle is in its unoperated position, and a one-way driving connection from said handle to said eccentric pin, whereby operation 20 of said handle is effective to unlock the door, but unlocking of the door by operation of said knob disengages said one-way driving connection to leave said handle in its unoperated position substantially flush with the outer surface of the 30 door.

2. In an automobile door, safety latching means comprising a pair of locking bolts, a disc pivotally mounted in said door and adapted to be rotated by a knob on the inner side of said door, pin and slot connections between said bolts and said disc whereby rotation of said disc is effective to operate said bolts, means acting on said disc to hold said bolts in their locking positions, an eccentric pin on the outer side of said disc, said door having a recess in its outer surface, a handle, means mounting said handle in said recess substantially flush with the outer surface of the door when said handle is in its unoperated position, said last-mentioned means including a lever pivoted in said door and operatively connected with said handle, an offset projection upon said lever resting in the normal closed position of the door on said eccentric pin, whereby operation of said handle is effective to unlock 50 the door, but unlocking of the door by operation of said knob simply serves to separate said projection from said eccentric pin to leave said handle in its unoperated position substantially flush with the outer surface of the door.
